UNITED STATES PATENT OFFICE.

WILLIAM A. TWINING, OF CLEVELAND, OHIO, ASSIGNOR TO THE NATIONAL PRINTING MACHINE COMPANY, OF CLEVELAND, OHIO, A CORPORATION OF OHIO.

TYPE SETTING AND DISTRIBUTING MACHINE.

1,036,751.

Specification of Letters Patent. Patented Aug. 27, 1912.

Application filed December 14, 1907. Serial No. 406,465.

To all whom it may concern:

Be it known that I, WILLIAM A. TWINING, a citizen of the United States, resident of Cleveland, county of Cuyahoga, and State of Ohio, have invented a new and useful Improvement in Type Setting and Distributing Machines, of which the following is a specification, the principle of the invention being herein explained and the best mode in 10 which I have contemplated applying that principle, so as to distinguish it from other inventions.

My present invention relates to improvements in printing mechanism and to a type setting and distributing device for use in conjunction therewith. In its general aspects such invention is more or less closely related to the subject-matter of two co-pending applications Serial No. 390,020, 20 filed August 24, 1907, and Serial No. 403,658 filed November 25, 1907. Among such general aspects may be enumerated firstly, the adaptability of the printing machine for office use and to print in imitation of type-writing where, as in the use named, the matter of alinement and justification is but of secondary importance; and, secondly, the employment of key-board mechanism in setting up the type in and distributing the type 25 from the printing member. The first aspect or characteristic above named is shared with a machine now largely employed and commercially known as the multigraph; while the second, in the particular embodiment illustrated in the two applications referred to, as well as herein, is unique. This particular embodiment comprehends, broadly speaking, the use of key-board mechanism to shift a type case adapted to 30 carry type in rows or columns, as the case may be, in such manner as to bring a selected type row or column into alinement with a relatively fixed discharge point. In the first of the two applications above 35 named, the printing member consists specifically of a rotary drum provided with a plurality of type receiving sockets respectively adapted to receive individual type, and the type case consists specifically of a 40 double set of superimposed cells adapted to hold the type assorted as to characters, and themselves interchangeable in position. In the machine of such application the key-board mechanism is adapted to shift the case 45 to place the desired type cell in alinement

with the discharge point and then either to remove a type from such cell and insert the same in a socket of the drum, or else, reversing its action, to withdraw a type from the latter and restore it to the type case. 60 The second type of machine, illustrated in the second application above referred to, is specifically an adaptation of my invention to the setting up and distributing of type in connection with a printing member of the 65 sort employed in the multigraph, wherein the type are held in undercut or recessed grooves into which the type are adapted to be inserted laterally and then shoved along to their proper positions longitudinally of such groove. In such second form of the invention I have retained the cylindrical or drum shaped type-holding and printing members that characterize the multigraph, not because they are necessarily the most 70 convenient or advantageous, even where my invention is not employed in conjunction therewith, but because as stated it was desired to illustrate the adaptation of the invention to the specific machine named. 75

In the present instance I desire to illustrate the employment of the invention in conjunction with a flat printing member in contradistinction to the rotatable drum shaped member of the two previous devices, in which however, the type are held in the same manner as in the multigraph, viz. in undercut grooves. Not only does a printing member or form of this sort present certain advantages over a rotary drum, as will be 80 readily apparent to those skilled in the art of printing, but in the corresponding modification of the type-holding member or case, required to adapt the same for use with such flat printing member, a number of advantages are secured not only in the more compact form attainable, but also in the simpler connections possible between such case and the key-board mechanism whereby the case 85 is shifted in the manner above described. 90

The general relation, as well as the objects, of the present invention having been thus set forth, the means entering into such invention will now be taken up, such means being hereinafter fully described and particularly pointed out in the claims. 100

The annexed drawings and the following description set forth in detail certain mechanism embodying the invention, such disclosed means constituting, however, but on

of various mechanical forms in which the principle of the invention may be used.

In said annexed drawings: Figure 1 represents my invention in plan view, a portion, 5 however, of the printing member, as also parts of a majority of the key levers, being broken away; Fig. 2 is a side elevation of the invention, a portion of the casing being broken away in order to reveal the construction 10 of the mechanism proper; Fig. 3 is a front elevation, a portion of the casing being again broken away and the key-board mechanism being substantially entirely removed in order to avoid confusion in the 15 illustration of the remaining mechanism; Fig. 4 is a perspective view of one member of the type case constituting a prime feature of the present invention; Fig. 5 is a perspective view of another member of such 20 case constituting specifically the outer supporting portion thereof; Fig. 6 is a view, on a larger scale, of the device for positioning the printing member, the plan of such view being indicated by the line 6—6, Fig. 3; 25 and Fig. 7 is a similar enlarged view of several elements entering into the construction of the type-transferring device, such elements being shown as disassembled.

Having reference, then, to Figs. 1, 2 and 30 3, first of all, attention will be directed to the construction and manner of mounting of the printing member which may thereupon be dismissed from all but general consideration. This, as stated, is flat instead of 35 in the form of a drum as heretofore and consists simply of a rectangular plate A provided with a plurality of transversely disposed undercut grooves, or channels a, within which type of suitable conformation may 40 be received and held by reason of their engagement therewith, as will be readily understood. Such printing member, or form A is slidably mounted on guides b in the general supporting frame B of the machine, 45 Fig. 3, the direction of movement in the frame being transverse to the type holding grooves aforesaid. Printing member A is furthermore entirely removable from guides b when so desired, from which construction 50 it will be apparent that when one form has been set up another may be inserted in its place if desired, the printing operation in either event being performed in a separate machine. The latter is not here illustrated, 55 inasmuch as it forms no part of the present invention. It is contemplated that by a proper construction of the grooves so as to hold the type with sufficient tightness to insure their accurate alinement, and by providing means for locking such type securely 60 in the grooves, the form in question may be adapted for use in regular printing operations as well as in the "office" printing outfit in mind. When the printing-member A 65 is properly mounted in the machine frame,

the type-holding grooves a thereon are designed to be in a plane with the point from which type are discharged, or transferred, from the type-case to be described later. Owing to the necessity of a support, such as 70 that afforded by frame B, at each side of the printing-member as well as of the type-case, it is not convenient to have the lateral edges of the two members in question contact. To sustain the type, while in transit across the intervening space, there is provided on the intermediate frame portion an extension b', Figs. 1 and 3, provided with a groove with 75 which the respective grooves of the type-case and printing member may be brought into register. So far as the latter is concerned, the alining of successive grooves thereon with the groove in extension b', thus marking the discharge point, is had by simply advancing the member step by step 80 along guides b. To this end a shaft A' is mounted in machine frame B, directly below member A and transversely of the same, and two pinions a', mounted near the respective ends of such shaft, are adapted to engage 85 with racks a² on the underside of the member. Intermittent rotative movement of shaft A' is derived from a key-lever A² oscillatorily mounted on an axis a³ and connected with the shaft by means of a pawl and ratchet device. The latter, together 90 with a stop, or locking mechanism, operating in conjunction therewith, is shown in detail in Fig. 6. Referring to this figure accordingly, the upper end a⁴ of lever A² will 95 be seen to have a cam-engagement with a pin a⁵ laterally projecting from a plunger a⁶. In the normal position of the lever, a compression spring a⁷ is adapted to raise the plunger into engagement with the adjacent 100 rack a² on the bottom of printing member A, such plunger being mounted in the arms of a bracket b¹², Fig. 3. Forward movement 105 of lever-end a⁴, however, such movement occurring upon depression of the lever, is effective to retract plunger a⁶ and leave the member free to move. A toothed dog, or pawl, a⁸, pivotally mounted upon the lever-end, and adapted to be raised by a tension 110 spring a⁹, is adapted to engage a ratchet wheel a¹⁰ upon shaft A' immediately after the member A is thus released, such dog being retained out of engagement with the ratchet wheel in the normal position of the lever by engagement with a pin a¹¹. 115

The construction of the type-case C, from 120 which type are designed to be fed to the printing member just described, and thence received again, will next be noticed. This case is mounted so as to be movable in the 125 general frame B of the machine in the same direction as the printing member A; but, inasmuch as movement of the type-case will obviously be more frequent, race-ways b² and balls b³ are provided so as to provide 130

ball-bearings as a means of supporting the case in the frame and render such movement as nearly frictionless as possible. The case comprises essentially two members C' and C^2 as illustrated respectively in Figs. 4 and 5. Of these the outermost supporting member C^2 , as it has been termed before, is in effect a rectangular box provided at its respective inner corners with vertically alined guides c that receive corresponding tongues c' on the outer corners of the inner member C' , or type case proper. The latter will thus be seen to be susceptible of two movements, one, in common with the case as a whole, in a direction parallel with that of the printing member, or transverse of the grooves a in the latter, and another movement in a plane vertical with respect to the plane of the first movement. The mechanism for securing these several movements will be noted more particularly presently. Advertising, then, to the construction of the type-case C' proper, the latter will be seen to consist, Fig. 4, of a frame in the form of a channel, consisting in other words of simply a bottom c^2 and two sides c^3 , the ends being open. Projecting inwardly from the sides of such frame are three pairs of vertically spaced trays, the members c^4 of each pair being in the same plane and separated from each other by an opening alined with the corresponding opening between the two remaining pairs. The distance between the superposed trays is such as to permit free lateral movement thereof with respect to the feed bar D of the transfer mechanism to be described later, just as the openings between the members of each pair are adapted to permit free vertical movement of the case as a whole with respect to such bar when such openings are alined with the latter. The construction of each of the trays which constitute the type holding elements, proper, of the case renders the same in effect a replica of the printing-member which has already been described. In other words, each tray is provided with a plurality of parallel type-receiving grooves, or ways c^5 , exactly similar to those in such printing member, and adapted by virtue of the two movements of the type-case to be brought into alinement with the groove in extension b' and thus with any predetermined groove a of the printing member or form.

It has been explained above how, in order to bring a selected type-groove c^5 in one of the lower shelves c^4 of the inner type case C' into alinement with the type-groove a in the printing member alined with the discharge point, it is necessary that the feed rack that operates in conjunction with the type-case should be adapted to enter both between the respective pairs of shelves or trays, and between the superposed trays in order to engage the type in such particular

groove. The vertical movement of the inner case accordingly must occur before the movement of translation in the horizontal plane that positions the particular groove, thus selected, in alinement with the groove of the printing member. The means whereby this vertical movement is effected will now be described, such means being independent of the key-board mechanism whereby the final selecting of the type groove is had.

Mounted laterally of the outer supporting member of the type-case is a rock-shaft c^6 supported in suitable brackets c^7 , Figs. 2, 3, and 5. Connected with this shaft at each end is a lever arm c^8 which extends inwardly to approximately the center of the type-case, the inner ends of each lever being connected with the inner ends of two oppositely disposed levers c^9 mounted on the inside of the case wall and bearing segmental gears c^{10} at their outer ends that mesh with vertical racks c^{11} attached to the corresponding corners of the inner type-case C' . Connection between levers c^8 and these segmental gear levers c^9 is had by means of pins c^{12} in the ends of the former extending through slots c^{13} in the case wall. A torsional spring c^{14} mounted upon the shaft c^6 and having its opposite ends fixedly secured in a collar on such shaft and the adjacent bracket is adapted to almost but not quite sustain the weight of the inner case so that the latter will be seen to be practically balanced; a very slight force will accordingly suffice to elevate the same, when such movement becomes necessary in order to render available either of the lower pairs of trays or shelves. This elevation is had by means of two keys c^{15} c^{16} , the first of which is mounted on the inner end of lever c^8 , and is adapted to depress the latter its full range so as to raise the lowermost pair of trays of the inner type case onto the operative level. The second key c^{16} is mounted on an independent lever c^{17} having its range of movement limited by a stop c^{22} , Fig. 3, and is adapted by virtue of connection of such lever with the inner end of the lever c^8 just referred to, to depress the latter a sufficient amount to raise the second or intermediate pair of trays of the inner type-case onto the operative level. A spring actuated catch c^{18} , Figs. 2 and 3, formed with two inwardly projecting teeth is adapted to engage the lever c^8 to hold the same in either of the two positions just mentioned. Upon withdrawing catch c^{18} the lever, and with it the case, return again to their normal positions in which the upper pair of trays are on the operative level. It will be understood that ordinarily the upper trays will be utilized for the characters most frequently employed, which in the case in hand would be lower case type. On the next lower pair

would be held the capitals and on the lower-most pair figures, the punctuation marks and other miscellaneous characters, requiring to be used the least frequently. It will be understood, of course, that various dispositions of the font of type may be made according to the particular use for which any model of the machine may be designed.

In view of the construction of inner type-case C', the case as a whole requires to be normally positioned so as to locate the vertically aligned spaces between the respective members of each pair of trays c⁴ directly beneath the bar D of the transfer mechanism. In a fixed plate b⁴, located directly below the outer type-case C² and constituting a part of the machine frame, there are accordingly mounted two reciprocable plungers b⁵ normally constrained by springs b⁶ to move oppositely in a direction parallel with that of the movement of such type-case. Oppositely disposed ends of these plungers are turned upwardly so as to be engaged, upon appropriate movement of the type-case by corresponding lugs c²⁰ extending downwardly from its under side.

It has already been indicated that keyboard mechanism is employed to shift the type case as a whole in order to bring any selected type row of the pair of trays c⁴ lying in the operative plane into alignment with the discharge point in order to permit the transfer of type from such row to the aligned groove in the printing member, or vice versa. This key-board mechanism is preferably mounted in a forward extension of that portion of the frame B wherein is supported the type case. Such mechanism comprises a plurality of levers E oscillatorily mounted upon a transverse shaft E' and provided at their forward extremities with keys e of the usual construction. Parallel with the shaft E' upon which the key levers are thus mounted, and substantially directly below the transfer mechanism D, is mounted a shaft E² provided with a plurality of segmental gears e' of which a portion project in a general forward direction and the remainder in a general rearward direction. The rear ends of the key levers are likewise formed into segmental gears e² respectively adapted to mesh with gears e' thus mounted upon the shaft, those gears that mesh with the rearwardly extending gears on the shaft facing obviously in an opposite direction from those meshing with the forwardly extending gears. Normally the gears e² borne by the key-levers do not mesh with those e' on the shaft E², their arcs being parts of circles properly tangent but not themselves touching; a very slight movement of any gear e², however, suffices to engage the corresponding gear e', while the shaft is left perfectly free to rotate so far as the other gears are concerned. Actu-

ation of the key levers E will accordingly effect a rotation of the shaft either forwardly or rearwardly and for a predetermined amount, depending upon the particular gear with which engagement is thus had. Such various rotation of the shaft is translated into corresponding reciprocable movement of the type-case C either forwardly or rearwardly from its normal position by means of a larger segmental gear e³ mounted upon one end of shaft E² (the left in Figs. 1 and 3) and meshing with a rack C³ on the underside of the outer supporting member C² of the type case. Having once determined which tier of trays c⁴ is to be employed by depressing the proper key, either c¹⁶ or c¹⁸, on the front of the type case, depression of the proper key of the keyboard mechanism just described will suffice to bring the corresponding type row of such tier into operative position with respect to the type discharge point and transfer mechanism D as will be obvious. Upon the release of the key, however, the type case is again restored to its normal position so far as movement in a horizontal plane is concerned, but not as to the tier being operated upon, the particular tier selected remaining in the operative plane as has been explained until another one is chosen.

In view of the necessity of securing an accurate alignment of the type rows of the selected tier of trays with the way of the printing drum whereon a line of type is being composed, it is necessary that the type-case be more accurately positioned or centered than is possible by the actuating means described. There is accordingly provided, adjacent to the rack C³ wherewith segmental gear e³ engages, a second rack C⁴, Figs. 2 and 3, with triangular or saw teeth e¹⁹ supported adjacent to the inner face of gear e³, Figs. 2 and 3, and so disposed with respect to a spring-pressed vertically reciprocable plunger e⁴ that when the latter engages any particular notch therein, a corresponding way or groove of the type-case will be in exact alignment with the type discharge point. Spring-pressed plunger e⁴, thus adapted to register with the notches of rack C⁴ in order to stop the movement of the type-case and accurately center the same, is normally held out of engagement with such rack by a lever E³, drawn down by a spring e¹⁵, and engaging a lug e⁵ projecting laterally from said plunger, as shown in Fig. 2. This lever forms a part of a universal bar E¹ constructed as usual in the form of a frame, the side members e⁶ of which lie within the respective sides of the machine frame and are pivotally mounted on the same shaft E' as the key levers. The universal bar e⁷, proper, lies transversely of the machine directly below the forward ends of the key levers E so that depression of the

115

120

125

130

universal bar is a second operation resulting from the striking of any key. One effect of such operation, it has already been seen, will be to permit the plunger to engage the 5 rack and center the type-case and lock the same against further movement.

Disposed transversely of the machine and adjacent to the lever thus controlling spring 10 pressed plunger e^4 is a short rock shaft e^8 , provided with a lever e^9 extending inwardly and likewise adapted to be actuated by the universal bar just described through a link connection e^{10} had with lever E^3 . Upon the other end of such rock shaft is mounted an 15 upwardly extending arm e^{11} , the upper extremity of which is forked and loosely engages a clutch disk e^{12} , Figs. 2 and 3, whereby connection of the shaft E^2 with the large 20 segmental gear e^3 is controlled, the result of actuation of the rock shaft by the universal bar being to render the clutch inoperative. The timing of such release and that of the 25 release of the spring pressed plunger are relatively so adjusted that the release of the clutch occurs just after the forward tooth of the notch in the rack C^4 , which it is desired to have engaged by the plunger e^4 , has passed the latter; the plunger, being released a moment later, will enter the selected 30 notch and center the type-case even though it may have passed a short distance beyond its proper stopping point.

For the reason that more or less momentum is acquired by the type-case in its to-and-fro movement, (although this momentum is considerably less than where a rotatable drum is employed owing to the maximum range of movement being shorter), I have deemed it advisable to provide other 40 heavier stop means supplementary to the rack C^4 and spring-pressed plunger e^4 , the primary function of these latter elements being to center the type-case. Such supplementary stop means comprise simply a plurality of vertical plungers b^7 reciprocably held in sleeves or bushings b^8 mounted in the frame plate b^4 beneath the type-case. There will be one such plunger for each key lever E , and the position of the plunger 45 transversely of the frame will be chosen so as to bring its lower end in loose contact with the rearwardly extending portion of such key, a spring b^9 serving both to maintain the plunger in its lower position and the key e of the lever in its normal elevated position. Only several of these plungers are illustrated, Figs. 2 and 3, in order to 50 avoid confusion. On the under side of the outer member C^2 of the type-case C are a plurality of studs e^{20} transversely distributed so as to be respectively alined with such plungers b^7 and engage therewith when raised by the depression of the corresponding key lever E . The position of each 55 stud e^{20} longitudinally of the case is so

chosen that the engagement with plunger b^7 will take place coincidently with the selected type row in the case being brought into alinement with the discharge point. By such engagement, it will accordingly be 70 seen, the type case is brought practically to a standstill before the centering device is called into operation at all, thus relieving the latter of considerable strain.

For effecting the transfer of the type, 75 either from the type-case to the printing member, or vice versa, when a groove of the one is alined with a groove of the other, any desired form of transfer mechanism may be employed. The mechanism D illustrated in the drawings, Figs. 1, 3 and 7, comprises essentially two alined feed racks or bars D' , D^2 disposed directly above the groove in extension b' that bridges the space between the type-case and printing member 80 and extending thence over said case and member, respectively. These racks are provided at their respective ends with slots d surrounding pins d' carried on the frame of the machine, the conformation of the slots 85 being such that when either rack is given an inward longitudinal movement it will be lowered and then advanced horizontally. The effect of this movement is the engagement of teeth d^2 on the under side of the 90 rack with a chaser d^3 one of which is slidably carried in each of the channels or ways of the type-case, and temporarily in the operatively alined channel of the printing member. Operation of either feed bar is 95 designed to effect a sufficient movement of the particular chaser engaged to advance the line of type, against which it presses, one type space, or, in other words, to move the type at the inner end of the channel or groove of the member thus affected into the groove in the extension b' and thus ultimately into the alined groove of the other member.

To actuate the respective racks D' , D^2 100 either to set up type or distribute type, as the case may be, a rock-arm d^4 borne by the inner end of a horizontal rock-shaft D^3 is provided. The upper end of such arm carries a pin d^5 that engages horizontal slots 105 d^6 in the inner overlapping ends of the racks. These slots are of sufficient length to permit inward movement of either rack thereby without interfering with the other rack, springs d^7 serving normally to retain 110 both bars in their outer positions. Slots d^8 are also of sufficient width to permit the bars the vertical movement incident to their longitudinal reciprocation. Rock shaft D^3 is mounted in the machine frame B and 115 projects some distance forwardly therefrom, Fig. 2. This forward end is additionally supported in a standard b^{11} and bears a cross-arm d^9 that is adapted to 120 optionally have its respective ends connected 125

with the corresponding side member of the universal-bar frame E⁴ by a link d⁹. To facilitate the changing of this connection the upper end of the link is provided with a 5 spring actuated pin d¹⁰ bearing a knob d¹¹ at its outer extremity, such pin being adapted to engage either of two apertures d¹², one in each end of the cross-arm. Depending upon the end with which connection is 10 thus had, depression of the universal bar, such as occurs as a second result of the depression of any key-lever E, will effect operation of the transfer mechanism either to compose type upon printing member A 15 or to distribute it to case C. Inasmuch as the way or ways of the type supply case appropriated to blank type for spacing can only be brought into alinement with the discharge point and transfer mechanism by 20 transverse movement of the case as a whole, the space bar e¹² corresponds in its manner of mounting and connections in all respects with the other key levers and is hence not distinguished therefrom in this description. 25

In connection with the key levers E it furthermore becomes desirable to provide means for preventing the actuation of more than one key at a time, owing to the damage that might thereby be caused the type-case shifting mechanism and the type-transferring mechanism. With this in view I employ the following expedient: A race-way F for balls f is provided on the inner 30 side of the front casing b¹² inclosing the key-board mechanism and immediately below the lowermost series of keys. Such race-way is of course intersected by the slits or openings in which the keys move, so that, 35 in effect, a series of inclosed brackets are provided for the retention of the balls. The size and number of the latter are eaged so as to leave a space between the ends of the race-way and the balls, when crowded together, just sufficient to permit the passage of a single key lever. Those levers that lie in a plane higher than the others are provided with a downwardly projecting lug e¹⁴ of the same thickness as the levers themselves, and the levers, or such lugs, as the 40 case may be, are adapted to enter the corresponding slits in the race-way immediately upon depression of the lever being attempted. Such depression will obviously 45 be possible for but one lever at a time, inasmuch as the depression of any one lug crowding the balls together in the race-way will effectively block the passage of another lever across such race-way. 50

55 The general operation of the machine should be fairly apparent from the foregoing description of the construction of its component parts and the individual operation of the same. Assuming, then, a printing member, or form, to be properly in-

serted in the guides therefore provided in the right hand side of the machine frame, any desired groove or way thereon can be brought into alinement with the transfer mechanism so as to permit the transfer of 60 type thereto from the type-case across the groove in the extension that bridges the intervening space between such member and type-case. Having thus positioned the printing member, the setting up of a line 65 of type is begun by first bringing the proper tier of type holding trays in the type case into the operative level, or, in other words, into the same plane as the printing member and such extension. This is done by the 70 depression of one or the other of the keys e¹⁵ e¹⁶ in front of the type case, unless, indeed, it is desired to utilize the type held in the upper of such tiers, in which event no 75 vertical adjustment of the type case at all is necessary. Selection of the desired type from among those held in the several grooves or ways of the particular tier thus operatively positioned is effected by depressing the corresponding key of the key-board 80 mechanism. Such operation is at the same time effective to lock the type-case in proper position and to discharge the type from the type-case into the groove onto the extension intermediate between the case and 85 the printing member. Successive type are thus transferred from the type case to the printing member until the line first brought into position has been filled. The printing member is thereupon advanced to bring the 90 next line into position by means of lever A², and the operation thus continued until the form is completely set up. When it is desired to reverse the operation and distribute the type from the form to the type-case, 95 the operation so far as the key-board mechanism is concerned is the same, the connection of the universal bar with the transfer mechanism being merely reversed so as to cause a withdrawal of the type from the member instead of feeding of the type thereto. The key-board mechanism now 100 serves to select the proper type row for the reception of the type, just as before it served to select the same preliminarily to the discharge of a type therefrom. Vertical positioning of the type-case to bring the respective tiers into the operation plane is had just as before, the operator being guided in the latter operation of distributing by a 105 copy of the printed matter before him so that a degree of facility in this operation equal to that in the setting up operation may be obviously obtained. 110

115 It should be stated that both in the specification and in the claims the term "printing member" is employed in a broad significance, it being intended to thereby designate the member whereon the type are assembled or composed, irrespective of whether such 120

member is used directly in the printing operation as would be the case in the illustrated machine described or whether said member be utilized merely to receive the 5 type pending composition, the latter being thereupon transferred to the chase or other type holder proper of a printing press of the ordinary kind. The term in question will accordingly be seen to comprehend such 10 modifications in the construction of the member as will facilitate its use in the latter connection.

Other modes of applying the principle of my invention may be employed instead of 15 the one explained, change being made as regards the mechanism herein disclosed, provided the means stated by any of the following claims or the equivalent of such stated means be employed.

20 I therefore particularly point out and distinctly claim as my invention:—

1. The combination with a type-case provided with ways respectively adapted to hold type assorted as to characters, of key- 25 board mechanism adapted to move said type-case rectilinearly to bring a selected character into alinement with a relatively fixed discharge point.

2. The combination of a type-case provided with ways respectively adapted to hold type assorted as to characters, means normally positioning said type-case, and key-board mechanism adapted to move said member rectilinearly from its normal position to bring a selected character into alinement with a relatively fixed discharge point.

3. In mechanism of the class described, a type-case comprising a plurality of superposed pairs of horizontally extending trays 40 provided with parallel ways adapted to carry rows of type, said pairs of trays being vertically spaced from each other and the trays of respective pairs being laterally separated by vertically aligned spaces, said 45 type-case being movable in a vertical direction to bring any one of said pairs of trays into a plane with a relatively fixed discharge point and in a direction transverse to such ways to bring a selected way in the member 50 thus positioned into alinement with such discharge point.

4. The combination with a flat member provided with parallel ways adapted to carry rows of type and movable in a direction angular with respect to said ways, of key-board mechanism adapted to thus move said member to bring a selected way into alinement with a relatively fixed discharge point.

5. The combination with a flat member provided with parallel ways adapted to carry rows of type and movable in a direction at right angles with respect to said ways, of key-board mechanism adapted to 65 thus move said member to bring a selected

way into alinement with a relatively fixed discharge point.

6. The combination of a type-case comprising a plurality of flat members spaced from each other in the direction of their flat 70 faces and provided with parallel ways adapted to carry rows of type, means adapted to position said type-case in the direction of such spacing to bring any one of said members into a plane with a relatively fixed 75 discharge point, and key-board mechanism adapted to move said case in a direction transverse to said ways to bring a selected way in the member thus positioned into alinement with such discharge point. 80

7. The combination of a type-case comprising a plurality of superposed horizontally extending trays vertically spaced from each other and provided with parallel ways adapted to carry rows of type, means adapted 85 to vertically position said type-case to bring any one of said trays into a plane with a relatively fixed discharge point and key-board mechanism adapted to move said case in a direction transverse to said ways to 90 bring a selected way in the tray thus positioned into alinement with such discharge point.

8. The combination of a type-case comprising a plurality of superposed pairs of 95 horizontally extending trays provided with parallel ways adapted to carry rows of type, said pairs of trays being vertically spaced from each other and the members of the respective pairs being laterally separated by 100 vertically aligned spaces, means adapted to vertically position said type-case to bring any one of said pairs of trays into a plane with a relatively fixed discharge point, and key-board mechanism adapted to move said case in a direction at right angles to said 105 ways to bring a selected way in the tray thus positioned into alinement with such discharge point.

9. The combination of a type-case composed of elements each adapted to hold rows of type assorted as to characters, means adapted to discharge any desired type from said case when properly positioned with reference thereto, and means adapted to move 110 said type-case in angularly related directions to thus position selected type, and thereupon to actuate said discharge means.

10. The combination of a type-case comprising a plurality of symmetrically disposed elements adapted to carry rows of type, means adapted to discharge type from any one of said elements when properly positioned with reference thereto, and independent means respectively adapted to 115 move said type-case in angularly related directions to thus position a selected type-carrying element, and thereupon to actuate said discharge means.

11. The combination of a type-case com- 120

prising a plurality of elements adapted to carry type, said elements being alined in two rectangularly related directions, means adapted to discharge type from any one of 5 said elements when properly positioned with reference thereto, means adapted to move said type-case in one such direction to bring an alined series of elements into the operative plane with respect to said type-discharge means, and other means adapted to move said type-case in the other direction to thus properly position a selected element of such series with respect to said type-discharge means and thereupon to actuate the 10 latter.

12. The combination of a type-case comprising a plurality of elements adapted to carry type, said elements being alined in two rectangularly related directions, means 20 adapted to discharge type from any one of said elements when properly positioned with reference thereto, means adapted to move said type-case in one such direction to bring an alined series of elements into the operative 25 plane with respect to said type-discharge means, and key-board mechanism adapted to move said type-case in the other direction to thus properly position a selected element of such series with respect to said type-discharge means and thereupon to actuate the 30 latter.

3. The combination of a type-case comprising a plurality of flat members spaced from each other in the direction of their 35 flat faces and provided with parallel ways adapted to carry rows of type, means adapted to discharge type from any one of said ways when properly positioned with respect thereto, means adapted to move said type-case in the direction of such spacing to bring any one of said members into the operative plane with respect to said type-discharge means, and key-board mechanism adapted 40 to move said type-case in a direction transverse to such ways to bring a selected way of the member thus positioned into proper position with said type discharge means, and thereupon to actuate the latter.

14. The combination of a type-case comprising a plurality of superposed horizontally extending trays vertically spaced from each other and provided with parallel ways 50 adapted to carry rows of type, a longitudinally reciprocable member parallel with such ways and adapted to discharge type from any one of the same when positioned adjacent to said member, means adapted to move said type-case in a vertical direction to bring any one of said trays into the operative plane with respect to said member, and key-board mechanism adapted to move said type-case in a direction transverse with respect to such ways to bring a selected way 60 of the tray thus positioned adjacent to said member, and thereupon to actuate the latter.

15. The combination of a type-case comprising a plurality of superposed pairs of horizontally extending trays provided with parallel ways adapted to carry rows of type, said pairs of trays being vertically spaced from each other and the trays of the respective pairs being laterally separated by vertically alined spaces, a reciprocable bar parallel with such ways and adapted to discharge type from any one of the same when positioned beneath said bar, the spaces between said pairs of trays and between the trays of each pair being respectively adapted to accommodate said bar, means adapted to move said type-case in a vertical direction to bring any one of said trays into the operative plane with respect to said bar, and key-board mechanism adapted to move said type-case in a direction transverse with respect to such ways to bring a selected way 70 of the tray thus positioned adjacent to said bar, and thereupon to actuate the latter.

16. In mechanism of the class described, a type-case comprising a supporting member and a type-holding member made up of a plurality of trays spaced from each other in the direction of their flat faces and provided with parallel ways adapted to carry rows of type, said type-holding member being movable on said supporting member in the direction of such spacing to bring any one of said trays into a plane with a relatively fixed discharge point, and said supporting member being movable in a direction transverse to such ways to bring a way in the 80 tray thus positioned into alinement with such discharge point.

17. In mechanism of the class described, a type-case comprising a movable supporting member, a type-holding member movably mounted upon said supporting member, counter-balancing means for said type-holding member, and means adapted to secure the latter in various elevated positions with respect to said supporting member.

18. In mechanism of the class described, a type-case comprising a movable supporting member, a type-holding member movably mounted upon said supporting member, resilient means tending to counterbalance said type-holding member, and means adapted to secure the latter in various elevated positions with respect to said supporting member.

19. In mechanism of the class described, a type-case comprising an outer movable supporting case provided with vertical guides, an inner type-holding case mounted between said guides, and means mounted on said outer case and engaging the respective 115 corners of said inner case for elevating the latter with respect to the former.

20. In mechanism of the class described, a type-case comprising an outer movable supporting case provided with vertical 120

guides, an inner type-holding case mounted between said guides, means mounted on said outer case and engaging the respective corners of said inner case for elevating the latter with respect to the former, and a catch coöperative with said means to secure said inner case in various elevated positions.

21. In mechanism of the class described, a type-case comprising an outer movable supporting case provided with vertical guides, an inner type-holding case mounted between said guides and provided with vertical racks near each corner, segmental gears mounted upon said outer case and engaging said racks, respectively, and a lever adapted to simultaneously actuate said gears to elevate said inner case in various elevated positions.

22. In mechanism of the class described, a type-case comprising an outer supporting case provided with vertical guides, an inner type-holding case mounted between said guides and provided with vertical racks near each corner, segmental gears mounted upon said outer case and engaging said racks, respectively, and a catch also coöperative with said elevating means and adapted to secure said inner case in various elevated positions.

23. In mechanism of the class described, a type-case comprising an outer supporting case provided with vertical guides, an inner type-holding case mounted between said

guides and provided with vertical racks near each corner, segmental gears mounted upon said outer case and engaging said racks, respectively, and two levers respectively adapted to simultaneously actuate said gears to elevate said inner case to different heights.

24. In mechanism of the class described, a type-case comprising an outer supporting case provided with vertical guides, an inner type-holding case mounted between said guides and provided with vertical racks near each corner, segmental gears mounted upon said outer case and engaging said racks, respectively, two levers respectively adapted to simultaneously actuate said gear to elevate said inner case to different heights, and a catch adapted to engage such elevating mechanism to retain said inner case at each of such heights.

25. In mechanism of the class described, a type-case comprising an outer supporting case provided with vertical guides, an inner type-holding case mounted between said guides and provided with a pair of opposed vertical racks on each of two opposite sides, said racks being located near the corners of said case, corresponding pairs of segmental gears mounted upon the sides of said outer case and engaging said racks, a rock shaft mounted upon said outer case transversely of said gears, and levers connecting said

pairs of gears, respectively, with said shaft, one of said levers serving as an actuating lever, whereby said inner case may be elevated to different heights.

26. In mechanism of the class described, a type-case comprising an outer supporting case provided with vertical guides, an inner type-holding case mounted between said guides and provided with a pair of opposed vertical racks on each of two opposite sides, said racks being located near the corners of said case, corresponding pairs of segmental gears mounted upon the sides of said outer case and engaging said racks, a rack shaft mounted upon said outer case transversely of said gears, levers connecting said pairs of gears, respectively, with said shaft, one of said levers serving as an actuating lever whereby said inner case may be elevated to a maximum height, and another lever connected with aforesaid lever but having a more limited movement, whereby said inner case may be elevated to a less height.

27. In mechanism of the class described, a type-case comprising an outer supporting case provided with vertical guides, an inner type-holding case mounted between said guides and provided with a pair of opposed vertical racks on each of two opposite sides, said racks being located near the corners of said case, corresponding pairs of segmental gears mounted upon the sides of said outer case and engaging said racks, a rock shaft mounted upon said outer case transversely of said gears, levers connecting said pairs of gears, respectively, with said shaft, one of said levers serving as an actuating lever whereby said inner case may be elevated to a maximum height, another lever connected with aforesaid lever but having a more limited movement, whereby said inner case may be elevated to a less height, and a catch adapted to variously engage aforesaid lever to sustain said inner case at each such height.

28. In mechanism of the class described, a type-case comprising an outer supporting case provided with vertical guides, an inner type-holding case mounted between said guides and provided with a pair of opposed vertical racks on each of two opposite sides, said racks being located near the corners of said case, corresponding pairs of segmental gears mounted upon the sides of said outer case and engaging said racks, a rock shaft mounted upon said outer case transversely of said gears, levers connecting said pairs of gears, respectively, with said shaft, one of said levers serving as an actuating lever whereby said inner case may be elevated to a maximum height, another lever connected with aforesaid lever but having a more limited movement, whereby said inner case may be elevated to a less height, a catch adapted to variously engage aforesaid lever to sus.

tain said inner case at each such height, and a torsion spring mounted upon said shaft and adapted to counterbalance said inner case.

5 29. The combination with a type-case comprising a supporting member, a type-holding member made up of superposed trays vertically spaced from each other and provided with parallel ways adapted to carry rows of type, said type-holding member being vertically movable in said supporting member to bring any one of said trays into a plane with a relatively fixed discharge point, and said supporting member 10 being movable in a direction transverse to such ways to bring any way in the tray thus positioned into alinement with such point; means borne by said supporting member adapted to secure said type-holding member in each position thereof; and key-board mechanism adapted to move said supporting member to bring a selected way into alinement with such discharge point.

15 30. The combination with a type-case comprising a supporting member, a type-holding member made up of superposed trays vertically spaced from each other and provided with parallel ways adapted to carry rows of type, said type-holding member being vertically movable in said supporting member to bring any one of said trays into a plane with a relatively fixed discharge point, and said supporting member being movable in a direction transverse to 20 such ways to bring any way in the tray thus positioned into alinement with such point; means borne by said supporting member adapted to secure said type-holding member in each position thereof; means normally positioning said supporting member; and key-board mechanism adapted to move said supporting member from its normal position to bring a selected way into alinement with such discharge point.

25 31. The combination with a type-case comprising a supporting member, a type-holding member made up of superposed trays vertically spaced from each other and provided with parallel ways adapted to carry rows of type, said type-holding member being vertically movable in said supporting member to bring any one of said trays into a plane with a relatively fixed discharge point, and said supporting member 30 being movable in a direction transverse to such ways to bring any way in the tray thus positioned into alinement with such point; means borne by said supporting member adapted to secure said type-holding member in each position thereof; means normally positioning said supporting member; and key-board mechanism adapted to move said supporting member from its normal position to bring a selected way into alinement with such discharge point; and a cen-

tering device adapted to hold said member against movement when thus positioned.

32. The combination with a type-case comprising a supporting member, a type-holding member made up of superposed trays vertically spaced from each other and provided with parallel ways adapted to carry rows of type, said type-holding member being vertically movable in said supporting member to bring any one of said trays into a plane with a relatively fixed discharge point, and said supporting member being movable in a direction transverse to such ways to bring any way in the tray thus positioned into alinement with such point; means borne by said supporting member adapted to secure said type-holding member in each position thereof; means normally positioning said supporting member; key-board mechanism adapted to move said supporting member from its normal position to bring a selected way into alinement with such discharge point; and a clutch adapted to control the connection of said mechanism with said member, said mechanism including a universal bar adapted to break such connection.

33. The combination with a type-case comprising a supporting member, a type-holding member made up of superposed trays vertically spaced from each other and provided with parallel ways adapted to carry rows of type, said type-holding member being vertically movable in said supporting member to bring any one of said trays into a plane with a relatively fixed discharge point, and said supporting member being movable in a direction transverse to such ways to bring any way in the tray thus positioned into alinement with such point; means borne by said supporting member adapted to secure said type-holding member in each position thereof; means normally positioning said supporting member; key-board mechanism adapted to move said supporting member from its normal position to bring a selected way into alinement with such discharge point; a clutch adapted to control the connection of said mechanism with said member; and a centering device adapted to hold said member against movement when a way is positioned as aforesaid, said mechanism including a universal bar adapted to actuate said clutch to break such connection and thereupon to render said centering device effective.

34. The combination of a frame, a type supply member provided with ways adapted to carry rows of type, said member being movably mounted in said frame so as to bring any desired way into alinement with a relatively fixed discharge point, and a flat printing member likewise provided with ways adapted to carry rows of type, said frame being formed with guides adapted to

removably support said printing member in a plane with such discharge point.

35. The combination of a frame, a type supply member provided with ways adapted 5 to carry rows of type; said member being movably mounted in said frame so as to bring any desired way into alinement with a relatively fixed discharge point, a flat printing member likewise provided with 10 ways adapted to carry rows of type, said frame being formed with guides adapted to removably support said printing member in a plane with such discharge point, and means adapted to intermittently advance 15 said printing member to aline successive ways thereon with such point.

36. The combination of a frame, a type supply member provided with ways adapted 20 to carry rows of type, said member being movably mounted in said frame so as to bring any desired way into alinement with a relatively fixed discharge point, a flat printing member likewise provided with 25 ways adapted to carry rows of type, said frame being formed with guides adapted to removably support said printing member in a plane with such discharge point, and means adapted to intermittently advance 30 said printing member to aline successive ways thereon with such point, such means including a rack on said member, a pinion meshing therewith, pawl and ratchet mechanism for rotating said pinion, and a lever adapted to actuate said mechanism.

35 37. The combination of a frame, a type supply member provided with ways adapted

to carry rows of type, said member being movably mounted in said frame so as to bring any desired way into alinement with a relatively fixed discharge point, a flat 40 printing member likewise provided with ways adapted to carry rows of type, said frame being formed with guides adapted to removably support said printing member in a plane with such discharge point, means 45 adapted to intermittently advance said printing member to aline successive ways thereon with such point, and means adapted to lock said member against movement.

38. The combination of a frame, a type supply member provided with ways adapted 50 to carry rows of type, said member being movably mounted in said frame so as to bring any desired way into alinement with a relatively fixed discharge point, a flat 55 printing member likewise provided with ways adapted to carry rows of type, said frame being formed with guides adapted to removably support said printing member in a plane with such discharge point, means 60 adapted to intermittently advance said printing member to aline successive ways thereon with such point, and means adapted to lock said member against movement, operation of said locking means being controlled by said advancing means.

Signed by me, this 13th day of December, 1907.

WILLIAM A. TWINING.
